(57) **CLAIM**

The ornamental design for a lighthead, as shown and described.

DESCRIPTION

FIG. 1 is a perspective view of a first embodiment of a lighthead;

FIG. 2 is a top plan view of the first embodiment of the lighthead;

FIG. 3 is a bottom plan view of the first embodiment of the lighthead;

FIG. 4 is a front view of the first embodiment of the lighthead, the opposite rear view being identical;

FIG. 5 is a right side view of the first embodiment of the lighthead, the opposite left side view being identical;

FIG. 6 is a perspective view of the first embodiment of the lighthead positioned on a representative mounting flange;

FIG. 7 is a perspective view of a second embodiment of the lighthead;

FIG. 8 is a top plan view of the second embodiment of the lighthead;

FIG. 9 is a bottom plan view of the second embodiment of the lighthead;

FIG. 10 is a front view of the second embodiment of the lighthead, the opposite rear view being identical;

FIG. 11 is a right side view of the second embodiment of the lighthead, the opposite left side view being identical;

FIG. 12 is a perspective view of the second embodiment of the lighthead positioned on a representative mounting flange;

FIG. 13 is a perspective view of a third embodiment of the lighthead;

FIG. 14 is a top plan view of the third embodiment of the lighthead;

FIG. 15 is a bottom plan view of the third embodiment of the lighthead;

FIG. 16 is a front view of the third embodiment of the lighthead, the opposite rear view being identical;

FIG. 17 is a right side view of the third embodiment of the lighthead, the opposite left side view being identical; and,

FIG. 18 is a perspective view of the third embodiment of the lighthead positioned on a representative mounting flange. The broken lines in the drawings illustrate portions of the lighthead or the environment related to the lighthead which form no part of the claimed design.
